Primary Examiner — Freda S Nunn(74) *Attorney, Agent, or Firm* — Bishop Diehl & Lee, Ltd.(57) **CLAIM**

The ornamental design for the air fryer housing, as shown and described.

DESCRIPTION

FIG. 1 is an isometric view of an air fryer housing showing the new design;

FIG. 2 is a front view of the air fryer housing as shown in FIG. 1;

FIG. 3 is a rear view of the air fryer housing shown in FIG. 1;

FIG. 4 is a left side view of the air fryer housing shown in FIG. 1;

FIG. 5 is a right side view of the air fryer housing shown in FIG. 1;

FIG. 6 is a top view of the air fryer housing shown in FIG. 1; and,

FIG. 7 is a bottom side view of the air fryer housing shown in FIG. 1.

The broken lines shown in the drawings form no part of the claimed design.
